ATTORNEY

UNITED STATES PATENT OFFICE.

ALOYSIUS M. ROSE, OF PHILADELPHIA, PENNSYLVANIA.

DESIGN FOR A PITCHER.

No. 38,836.

Specification for Design.

Patented Sept. 24, 1907.

Application filed July 23, 1907. Serial No. 385,227. Term of patent 3½ years.

To all whom it may concern:

Be it known that I, Aloysius M. Rose, a citizen of the United States, residing at Philadelphia, in the county of Philadelphia and State of Pennsylvania, have invented a new and ornamental Design for Pitchers, of which the following is a specification, reference being had to the accompanying drawing forming a part thereof.

The figure is a perspective of a pitcher showing my new design.

I claim

The ornamental design for a pitcher, as shown.

ALOYSIUS M. ROSE.
